UNITED STATES PATENT OFFICE.

ANTON HOVORKA, OF CHICAGO, ILLINOIS.

CRATE.

1,081,831.

Specification of Letter's Patent.

Patented Dec. 16, 1913.

Application filed January 20, 1913. Serial No. 743,113.

To all whom it may concern:

Be it known that I, ANTON HOVORKA, a citizen of the United States, residing at Chicago, in the county of Cook and State 5 of Illinois, have invented certain new and useful Improvements in Crates, of which the following is a specification.

This invention relates to knock-down crates having pivotally connected side and 10 end walls and a removable top and bottom, and its object is to provide a novel and improved fastening for the top and bottom of the crate, whereby said parts are securely held in place when the crate is set up, and 15 which also permits said parts to be easily and quickly removed when it is desired to fold the crate.

In order that the invention may be fully understood, reference is had to the accompanying drawing in which—

Figure 1 is a plan view of the crate. Fig. 2 is a side elevation thereof. Fig. 3 is an end view. Fig. 4 is a detail in perspective showing the fastening for the top.

As shown in the drawing the walls of the crate are constructed of slats, the side walls comprising top and bottom slats 10 and 11, respectively, connected by laterally spaced vertical slats 12, the latter being secured to 25 the inner faces of the top and bottom slats. The end walls are composed of top and bottom slats 13 and 14, respectively, and vertical slats 15 connected in the same manner as the slats forming the side walls.

The side and end walls are hinged together at their meeting vertical edges by means of linked staples 16. Any other suitable hinge or pivot connection may be provided.

The top of the crate is constructed of a pair of longitudinal side slats 17 connected by transverse slats 18, the latter being secured to the bottom of the former.

The bottom of the crate is constructed in 45 the same manner as the top.

The side walls of the crate are higher than the end walls, and the top is dimensioned so that it fits between the vertical slats 12 of the side walls and rests on the 50 top slats 13 of the end walls. The bottom fits in a similar manner between the side walls and against the bottom edge of the bottom slats 14 of the end walls.

The top and bottom are not permanently 55 fastened to the side and end walls of the

crate, but are removable therefrom in order that said side and end walls may be folded.

The following means is provided for fastening the top in place when the crate is set up for use: In the inner face of the top 60 slats 10 are vertical grooves in which are mounted stems 19 having lateral bends 20 and 21, respectively, at their ends, said bends being in opposite directions and forming hooks. The extremity of the bend 21 has a 65 downward bend 22 for a purpose to be presently described. The grooves in which the stems are mounted are in that portion of the slats 10 which is lapped by the vertical slats 12, the latter therefore covering the 70 grooves and serving to retain the stems therein. The stems are loose in the grooves so that they may be rotated therein. The hooks 21 are so located that they may engage the top of the crate when said top is in 75 place, and the hooks 20 are adapted to engage under the top slat 10. The slats 17 have top grooves 23 forming seats for the hooks 21, said grooves having deepened portions at their inner ends to receive the 80 terminal portions 22 of said hooks.

The fastening means for the crate bottom are the same as the top fastenings herein described.

Before fastening the top in place, the 85 stems 19 are turned so that the hooks 21 extend obliquely across the top edge of the slats 12 without projecting beyond the inner face thereof, with the terminal 22 extending alongside one of the vertical edges 90 of said slats. With the fastenings in this position, the crate is unobstructed on the inside, and the top may be put in place without interference. After putting the top in place, the hooks 21 are swung around to seat 95 in the grooves 23, the terminals 22 seating in the deepened portions thereof. By pressing down on the top, the hooks may be swung around into holding position. The hooks can also be made resilient so that 100 they may be sprung into holding position. When the hooks 21 are placed in holding position, the hooks 20 come into position beneath the slats 10, which completes the fastening. The top is now securely held in 105 place but it can be easily and quickly removed by swinging the hooks back to clear the top of the crate and the slats 10.

Curved grooves 24, extending from the inner edge of the slats 17 to the deepened por- 110

tions of the grooves 23 may be provided for facilitating the operation of the fastenings.

I claim:

1. A crate having side walls composed of top and bottom slats and vertical slats connecting the same, said vertical slats lapping the top slats on one side, and the lapped portions of said top slats having grooves, stems rotatably mounted in the grooves and having oppositely extending hooks at their ends, and a removable top for the crate, said top fitting between the side walls and having seats to receive the hooks on one end of the aforesaid stems, the hooks on the other end 10 of the stems engaging beneath the aforesaid top slats of the side walls when the first-mentioned hooks engage their seats.

2. A crate having side walls composed of top and bottom slats and vertical slats connecting the same, said vertical slats lapping the top slats on one side, and the lapped portions of said top slats having grooves, stems rotatably mounted in the grooves and having oppositely extending hooks at their 20 ends, and a removable top for the crate, said top fitting between the side walls and being engageable by the hooks on one end of the aforesaid stems, the hooks on the other ends 25 of the stems engaging beneath the aforesaid top slats of the side walls.

3. A crate having side walls composed of top and bottom slats and vertical slats connecting the same, said vertical slats lapping the top slats on one side, and the lapped portions of said top slats having grooves, stems rotatably mounted in the grooves and having oppositely extending hooks at their 35 ends, the hooks at one end of the stems having inturned extremities, and a removable top for the crate, said top fitting between the side walls and having grooves to receive the hooks having the inturned extremities, said grooves having deepened portions to receive 40 said extremities, the hooks on the other end of the stems engaging beneath the aforesaid top slats of the side walls when the first-mentioned hooks engage the top.

4. A crate having side walls composed of

top and bottom slats and vertical slats connecting the same, said vertical slats lapping the top slats on one side, and the lapped portions of said top slats having grooves, stems mounted in the grooves and having oppositely extending hooks at their ends, the hooks at one end of the stems having in-turned extremities, and a removable top for the crate, said top fitting between the side walls and having grooves to receive the hooks having the inturned extremities, said grooves having deepened portions to receive 50 said extremities, the hooks on the other end of the stems engaging beneath the aforesaid top slats of the side walls when the first-mentioned hooks engage the top, said stems being rotatable to disengage the hooks, the 55 hooks having the inturned extremities being adjustable to lie alongside one edge of the vertical slats of the side walls when disengaged from the top.

5. A crate having side walls composed of top and bottom slats and vertical slats connecting the same, said vertical slats lapping the top slats on one side, and the lapped portions of said top slats having grooves, stems mounted in the grooves and having 70 oppositely extending hooks at their ends, the hooks at one end of the stems having in-turned extremities, and a removable top for the crate, said top fitting between the side walls and being engageable by the hooks 75 having the inturned extremities, the hooks on the other end of the stems engaging beneath the aforesaid top slats of the side walls when the first-mentioned hooks engage the top, said stems being rotatable to disengage the hooks, the hooks having the in-turned extremities being adjustable to lie alongside one edge of the vertical slats of the side walls when disengaged from the top.

In testimony whereof I affix my signature 90 in presence of two witnesses.

ANTON HOVORKA.
